US0D1083842S

(12) **United States Design Patent** (10) Patent No.: **US D1,083,842 S**
(45) Date of Patent: ** Jul. 15, 2025

(54) **PLIABLE BOOT CONNECTOR**

(71) Applicant: **Joseph Davitian**, Queen Creek, AZ (US)

(72) Inventor: **Joseph Davitian**, Queen Creek, AZ (US)

(**) Term: **15 Years**

(21) Appl. No.: **29/894,462**

(22) Filed: **Jun. 9, 2023**

(51) LOC (15) Cl. **13-03**

(52) U.S. Cl.

USPC **D13/156**

(58) **Field of Classification Search**

USPC D13/156, 133, 150, 177

CPC H01R 13/5205; H01R 13/5221
